BAFFLE SYSTEM FOR STIRLING BOILERS.

1,070,478.

Specification of Letters Patent. Patented Aug. 19, 1913.

Application filed January 2, 1913. Serial No. 739,721.

To all whom it may concern.

Be it known that I, DAVID S. JACOBUS, a citizen of the United States, residing at Jersey City, in the county of Hudson and State of New Jersey, have invented certain new and useful Improvements in Baffle Systems for Stirling Boilers, of which the following is a specification.

My invention relates to a system of special baffles and water circulators for use in connection with Stirling boilers, and will be understood by reference to the accompanying drawings in which—

Figure 1 is a side elevation, partly in section, of a Stirling boiler with the system of baffling designed by me; Fig. 2, a similar view showing a slight modification in the inclination of the tubes and the baffling; and Fig. 3, face and edge views of one of the baffle plates.

Similar reference numerals indicate similar parts in the several views.

Referring to Fig. 1, the numeral 1 designates the walls of the boiler setting; 2 the furnace; 3, 4 and 5 banks of generating tubes expanded at their lower ends into a mud drum 6 and at their upper ends into steam and water drums 7, 8 and 9 respectively. These latter drums are connected by water circulators 10 and 11, and steam circulators 12. A covering of fire bricks 10' and 11' resting on the water circulator tubes 10 and 11 prevents the gases passing above these tubes. A steam main 13 leads from the central drum 8 to the cross box 14 of a superheater 15 placed in the upper part of the space between the front and middle banks of tubes. In the standard Stirling boiler a baffle extends along the rear tubes of the front bank upwardly from the drum 6 to near the upper end of the tubes, and a second baffle extends from the drum 8 along the rear tubes of the middle bank 4 to near the lower end of the tubes, these two baffles guiding the gases up the first bank of tubes, down the middle bank, and up the rear bank. To increase the heat transfer rate and the efficiency of the boiler I have provided the following described system of baffling

whereby the gases are made to cross and recross the tubes a greater number of times than with the normal baffling. Extending from the mud drum 6 nearly to the top of the first bank of tubes and resting against the rear tubes, is the usual baffle 16. Instead of the usual baffle resting on the rear tubes of the middle bank I have placed a baffle 17, made of plain tiles, along the front row of tubes of the rear bank and extending from drum 9 nearly to the bottom of the rear bank. This permits a full sweep of the gases across the upper part of all the tubes of the middle bank. To cause the gases to cross and recross the tubes of the middle and rear banks I introduce a cross baffle 18 extending laterally from baffle 16 among the tubes of the middle bank and below this, and in staggered relation thereto, a second cross baffle 19 extending laterally from baffle 17 among the tubes of the middle bank. I also introduce a lower cross baffle 20 extending laterally from the lower part of baffle 17 among the tubes of the rear bank, and above this a second baffle 21 extending from the rear wall of the setting to or among the tubes of the rear bank. The cross baffles may be of iron or other refractory substance supported in part by clamps 22 fastened to the tubes and made up of sections which can be introduced sideways between the tubes and turned at right angles to bring them in place between the tubes. In Fig. 3, I have shown a face and edge view of one of the sections.

In Fig. 2, the upper cross baffle 23 in the middle bank of tubes extends entirely across the bank to the superheater box 14 and a narrow shelf 24 is placed between the two superheater boxes, as shown, to prevent the gases passing downwardly to the lower part of the middle bank. Instead of resting the baffle on the tubes of the rear bank, as in Fig. 1, I have modified that baffle by extending baffle 25 from drum 9 down to the rear tubes of the middle bank, and by supporting it upon a beam or cross piece 26. The lower cross baffle 19 in Fig. 2, is substantially the same as in Fig. 1, but the cross

baffle 27 at the lower part of the rear bank is inclined downwardly instead of being substantially at right angles to the tubes. A shelf 28 extends from the rear wall of the 5 setting to the tubes of the rear bank.

In both boilers above described the gases from the furnace are guided up the front bank of tubes, deflected across the super-heater tubes into and across the top of the 10 middle bank, down the latter and up the rear bank to the stack outlet 29. While traversing the middle and rear banks in the general direction of their length, the gases are made to cross and recross the 15 tubes so as to contact with practically the entire heating surface.

The system of baffling above described has been tried out in practice and has led to the desired result, namely, an increase in heat 20 transfer rate over that accomplished with the ordinary or normal baffles of the Stirling boiler.

In the use of the special baffling described, the temperature of the gases which come in 25 contact with the rear steam and water drum is much higher than with the standard baffling, and to make sure that there shall be no overheating of this drum the circulators 11 are introduced and form an important 30 part of the invention. In operating the boiler at high capacities the water level in the rear steam and water drum is lower than in the others and adding the water circulators 11 provides for a flow of water from 35 the middle to the rear drum and for the cooling of the rear drum by the circulation of this water. The overheating of the rear drum is also guarded against by the use of protecting tiling 30.

40 My invention is not limited to the exact arrangement of cross baffles shown in the second and third passes of the boiler, but applies to a special construction of the boiler where the water circulating tubes 11 are placed between the middle and rear 45 steam and water drums, and cross baffles are employed in either the second or third bank of tubes, or both of said banks, in combination with a baffle between the second and 50 third banks to cause the gases to flow first over the second and then over the third bank of tubes.

What I claim and desire to secure by Letters Patent of the United States is:—

55 1. A Stirling boiler comprising three banks of generating tubes, a drum into which the lower ends of the tubes are expanded, steam and water drums into which the upper ends of the tubes are expanded, 60 water circulators between both front and middle and middle and rear steam and water drums, a baffle placed back of the first bank of tubes to direct the gases to the upper part of said tubes, a cross baffle extend-

ing from said first named baffle into and 65 among the tubes of the middle bank, a baffle extending downward from the rear steam and water drum, cross baffles extending laterally from said rear baffle, one of said cross baffles being at the lower part of the tubes 70 of the middle bank and the other at the lower part of the tubes of the rear bank, and a fourth cross baffle extending from the rear wall of the setting to or across the rear bank of tubes at the upper part thereof, whereby 75 the gases are made to cross and recross the tubes of both the middle and rear banks three times while traveling in the general direction of their length.

2. A Stirling boiler comprising three 80 banks of generating tubes, a drum into which the lower ends of the tubes are expanded, steam and water drums into which the upper ends of the tubes are expanded, 85 water circulators between both front and middle and middle and rear steam and water drums, a baffle placed back of the first bank of tubes to direct the gases to the upper part of said tubes, a cross baffle extending from said first named baffle into and 90 among the tubes of the middle bank, a baffle extending downward from the rear steam and water drum, a protecting covering of tiling or other refractory material at the front of the rear steam and water drum, 95 cross baffles extending laterally from said rear baffle, one of said cross baffles being at the lower part of the tubes of the middle bank and the other at the lower part of the tubes of the rear bank, and a fourth cross 100 baffle extending from the rear wall of the setting to or across the rear bank of tubes at the upper part thereof, whereby the gases are made to cross and recross the tubes of both the middle and rear banks three times 105 while traveling in the general direction of their length.

3. A Stirling boiler comprising three 110 banks of generating tubes, a drum into which the lower ends of the tubes are expanded, steam and water drums into which the upper ends of the tubes are expanded, 115 water circulators between both front and middle and middle and rear steam and water drums, a baffle to direct the gases to the upper part of the first bank of tubes, cross baffles in the third bank of tubes, and a baffle between the second and third bank of tubes for causing the gases to flow first over the second and then over the third bank of tubes. 120

4. A Stirling boiler comprising three 125 banks of generating tubes, a drum into which the lower ends of the tubes are expanded, steam and water drums into which the upper ends of the tubes are expanded, water circulators between both front and middle and middle and rear steam and water drums, a baffle to direct the gases to the

upper part of the first bank of tubes, cross baffles in the third bank of tubes, and a baffle between the second and third bank of tubes extending downward from the rear steam 5 and water drum to direct the gases downward to the bottom of the second bank of tubes.

In testimony whereof I have hereunto signed my name in the presence of two subscribing witnesses.

DAVID S. JACOBUS.
